US00D897269S

(12) **United States Design Patent** (10) **Patent No.:** **US D897,269 S**
(45) **Date of Patent:** **** Sep. 29, 2020**

(54) **AIRCRAFT**

(71) Applicant: **BARZAN HOLDINGS QSTP LLC**,
Doha (QA)

(72) Inventors: **Alfred Schmiderer**, Berlin (DE);
Reiner Stemme, Berlin (DE)

(73) Assignee: **BARZAN HOLDINGS QSTP LLC**,
Doha (QA)

(**) Term: **15 Years**

(21) Appl. No.: **29/664,800**

(22) Filed: **Sep. 27, 2018**

Related U.S. Application Data

(60) Division of application No. 29/635,687, filed on Feb. 1, 2018, now Pat. No. Des. 833,364, which is a continuation of application No. 29/569,827, filed on Jun. 30, 2016, now Pat. No. Des. 809,448.

(57) **CLAIM**

We claim the ornamental design for an aircraft, as shown and described.

DESCRIPTION

FIG. 1 is a side view for an aircraft, showing the new design, a side view of the reverse side is a mirror image of the illustrated side;

FIG. 2 is a front view of the aircraft;

FIG. 3 is a front view of a starboard portion of the aircraft;

FIG. 4 is a front view of a port portion of the aircraft;

FIG. 5 is a rear view of the aircraft;

FIG. 6 is a rear view of a starboard portion of the aircraft;

FIG. 7 is a rear view of a port portion of the aircraft;

FIG. 8 is a top view of the aircraft;

FIG. 9 is a top view of a starboard portion of the aircraft;

FIG. 10 is a top view of a port portion of the aircraft;

FIG. 11 is a bottom view of the aircraft;

FIG. 12 is a bottom view of a starboard portion of the aircraft; and,

FIG. 13 is a bottom view of a port portion of the aircraft. The broken lines shown in the drawings illustrate portions of the aircraft that do not form part of the claimed design.

1 Claim, 13 Drawing Sheets
